UNITED STATES PATENT OFFICE.

FRITZ RUNDQUIST, OF TOLEDO, OHIO, ASSIGNOR, BY MESNE ASSIGNMENTS, TO THE WILLYS-OVERLAND COMPANY, OF TOLEDO, OHIO, A CORPORATION OF OHIO.

FENDER-VIZOR-WIRING-IN MACHINE.

1,112,164.

Specification of Letters Patent. Patented Sept. 29, 1914.

Application filed August 11, 1913. Serial No. 784,162.

To all whom it may concern:

Be it known that I, FRITZ RUNDQUIST, a citizen of the United States, and a resident of Toledo, in the county of Lucas and State 5 of Ohio, have invented a certain new and useful Fender-Vizor-Wiring-In Machine; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates particularly to a machine for connecting the vizor portions of fender flanges to fender bodies without the use of rivets and at the same time securing a reinforcing wire thereto at or adjacent 20 to the point of connection, but is not restricted to such use as it may be employed in any connection for which it may be adapted or appropriate.

It has heretofore been the practice so far 25 as I am aware to attach the vizors to fender bodies by hand by means of riveting, electric welding or the like, and such operation has not only been exceedingly slow and difficult, but has required the work of at least 30 two persons to perform the same.

The object of my invention is the provision of a simple and efficient machine which is quickly operable in an automatic or semi-automatic manner to securely attach 35 the vizors to fender bodies and wire the same at the point of connection without the use of rivets, electric welding or equivalent means of securing such parts together, whereby to materially simplify, quicken and 40 cheapen the manufacture of such bodies and to lessen the labor incident thereto.

Further objects will be apparent from the following detailed description.

The invention is fully described in the 45 following specification, and while, in its broader aspect, it is capable of embodiment in numerous forms, a preferred embodiment thereof is illustrated in the accompanying drawings, in which,—

50 Figure 1 is a plan view of a machine embodying the invention with a part broken away. Fig. 2 is a front elevation thereof with the parts in inoperative position and portions broken away. Fig. 3 is an enlarged 55 section on the line x—x in Fig. 1. Fig. 4

is an enlarged side elevation of a machine with parts broken away and with a fender body shown in dotted lines thereon. Fig. 5 is an enlarged vertical section on the line y—y in Fig. 1, with the parts in work co-acting positions. Figs. 6 and 7 are assembled details of portions of the control mechanism with parts broken away, and Fig. 8 is an enlarged sectional detail of the work wiring-in parts, with the work piece being 65 operated on in section.

Referring to the drawings, 1 designates a table or frame top, which is supported by legs 2 and has a work supporting die or part 3 secured to and extending from one side thereof, the outer edge of such die being of semi-circular form, as best shown in Fig. 1. The die 3 is of suitable shape to support and conform to the front end portion of the front fender of an automobile and has its outer or semi-circular edge provided with an upstanding bead or ledge 4 within which the front rounded edge of a fender is intended to closely seat when the fender is placed in inverted position on the die. 70 A work supporting member 5 extends upward and rearward from the rear edge of the table 1 to support the upwardly curving rear end portion of the fender when positioned on the table.

A fender is firmly clamped to the die or table part 3 by clamping fingers 6—6, one of which is disposed at each side of the part 3 at the rear of the curved edge 4 of such part in position to engage over the side bead of the fender body, such bead being preferably formed thereon before the fender is placed on the table preparatory to having the vizor secured thereto. The clamping fingers 6 are carried by eccentric rods 7, which extend 75 down through suitable bearing openings in the frame top 1 and have their lower ends provided with frames 7* forming openings in which respective eccentrics 8 on a rock-shaft 9 work, whereby the clamping fingers are raised and lowered upon a rocking of the shaft 9. The shaft 9 is mounted in suitable frame parts 10 beneath the table 1 and carries a crank 11 at its outer end in convenient reach of the operator.

Rigidly depending from the extension part 3 of the table 1 in concentric relation to the semi-circular bead 4 of such part is a stub-shaft 12 from which a head 13 transversely projects for free semi-circular move- 110

ments around the outer edge of the part 3, such head having its inner end loosely journaled on the stub-shaft 12 beneath the part 3. The head 13 carries an edge beading or 5 wire rolling-in roll 14, such roll being laterally movable into position for an edge thereof to work over and inwardly beyond the bead 4 of the work supporting die 3, and has a stem projecting therefrom in a diagonally disposed opening in the head 13 and 10 connecting, in the present instance, to a shaft part 15, which is mounted in a bearing-block 16 within the head opening for limited axial movements. A pivot pin or 15 screw 16^a projects through a portion of the head 13 and into the bearing-block 16 to pivotally carry it and the shaft part 15 for transverse swinging movements relative to the head 13 for the purpose hereinafter de- 20 scribed. The shaft part 15 has its lower end projected without the lower portion of the head and carrying a bevel gear 17, a stop collar 18, and a coiled compression spring 19 between said collar and gear. The spring 19 25 causes the roll 14 to have a yielding downward pressure on the edge bead *a* of the fender A. The vizor flange of the fender is designated *b* and the reinforcing wire in the edge bead of the fender is designated *c* 30 in Figs 5 and 8.

A bearing-block 20 is carried by the head 13 at its under side and mounted in this is a shaft 21, which carries a bevel gear 22 at its outer end in mesh with the gear 17 and a 35 preferably smaller bevel gear 23 at its inner end in mesh with a segmental bevel gear 24 that is fixedly mounted on the lower reduced end portion of the stub-shaft 12, being secured thereto by a nut 25, which threads on 40 the lower reduced end portion of the shaft.

It is evident that the connecting of the roller shaft 15 to the stationary gear 24 in this manner causes a rotation of the roller 14 in first one and then the other direction as 45 the head 13 has forward and backward orbital swinging movements around the outer end portion of the table part 3.

A work-holding roll 26 is carried at the upper end portion of a vertically swinging 50 arm 27 in position to be swung downwardly into lateral bearing contact with the inner side of the bead *a* in opposition to the beading-roll 14, the arms 27 being pivoted, as at 28, to an extension-block or part 29, 55 which is carried on the upper side of the head 13. The work-holding roll 26 is carried by a spindle 30, which depends from and is attached to the upper free end portion of the arm 27 in any suitable 60 manner. The lower or outer end portion of the arm 27 is of yoke or forked form to adapt it to straddle the outer end portion of the block or bearing part 29, and a lever member 31 is mounted on the shaft or pin 28 65 with the arm 27, and has its outer or long

arm extending between and beyond the forked end portion of the arm 27 in the direction of projection thereof. The inner end of the lever member 31 is in the form of a short arm 31^a, which receives the outward 70 thrust of a plunger 32 that is mounted in an opening 33 in the part 29 and has its outward movements influenced by a coiled compression spring 34, which is mounted in the opening therewith, as best shown in Fig. 5. 75 A thrust part 34^a is disposed in the inner end portion of the opening 33 to receive the inner end thrust of the spring 34 and bears against a bearing block 14^a on the spindle or shaft of the roll 14 to tend to move the roll 80 14 transversely to work coacting position when the lever member 31 has spring compressing movements. A pair of coiled contractile springs 27^a connect the levers 27 and 31 below the pin 28 with the shaft of the 85 roll 14 to tend to hold all of such parts in inoperative positions, as shown in Fig. 5.

A horizontal shaft 35 is journaled in a bearing-block 36 that is secured to the outer end of the head 13 and a rock-finger 37 is 90 carried by such shaft for rocking movements therewith within a recess in the outer side of the block 36. This finger is positioned to have contact at its outer end with the inner side of the lower portion of the 95 arm or lever 27 to swing such arm into position for its roll 26 to have contact with a work piece when the finger is swung outward. The finger 37 is provided in its outer end with a socket in which a detent or 100 spring plunger 37^a is mounted for yielding compressing movements within the finger. This plunger is intended to coact with the long arm of the lever 31, when the finger is swung outward, to cause a swinging of the 105 lever 31 with the lever 27 and a consequent inward forcing of the spring plunger with which the short arm of the lever 31 has contact whereby to yieldingly move the beading roll 14 into work coacting position. 110

The shaft 35 carries a segmental gear 38 at the rear end thereof, and such gear meshes with a gear 39 on the outer end portion of the shaft 9, whereby a rocking of the crank-arm 11 to move the clamping 115 fingers 6, 6 into clamping engagement with a work piece will impart an outward rocking movement to the finger 37 to throw the work coacting rolls 14 and 26 into work engaging positions. 120

A driven shaft 40 is journaled in suitable bearings beneath the table 1 lengthwise thereof and carries a worm 41 in mesh with a worm-wheel 42 that is loosely journaled on the stub-shaft 12 above the inner end 125 portion of the head 13 and is fixed to such head for turning movements therewith. A pair of loose bevel-gears 43 are carried in spaced relation by the shaft 40 and are continuously driven in reverse direction by a 130

bevel pinion 44 on a drive-shaft 45, which is journaled beneath the table 1 and extends at right angles to the shaft 40. A belt-pulley 46 is carried by the shaft 45 at its outer end to enable it to be connected to a line shaft, or power may be communicated thereto in any other suitable manner. Each of the gears 43 is provided on the inner end of its hub with a clutch surface 47, and feathered on the shaft 40 for axial shifting movements between the gears 43 is a clutch-member 48, which may be shifted into clutch engagement with one or the other of the gears 43, as desired, whereby 10 to effect a driving of the shaft 40 in either direction from a continuous rotation of the shaft 45 in one direction.

The shifting movements of the clutch-member 48 are controlled by a shift-lever 49, which is fulcrumed, as at 50, to a bracket 51 depending from the under side of the table 1. The lower or free end of the shift-lever 49 is connected by a rod 52 to a block or finger 53, which is fixed to and projects transversely from a shift-rod 54. The rod or shaft 54 is mounted for axial shifting movements in the frame parts 10, 10 and is connected at one end to a control-lever 55, which extends transversely thereof over a stationary frame part 56, to which it is fulcrumed, as at 57, with its rear end in position to be grasped by the operator, as shown in Figs. 3, 4 and 7. A spring pressed detent 58 is mounted in the lower end of the bracket 51 beneath the free end of the shift-lever 49 in position to coact with such lever upon a swinging thereof, to tend to stop its swinging when the clutch member 48 is in neutral position. The lever coacting end of 35 the detent 58 is oppositely beveled or of inverted V-shape, and the adjacent end of the lever 49 is correspondingly shaped. The point of the detent 58 is so positioned relative to the throw of the lower pointed end of 40 lever 49 that a greater movement will be required to throw the end of the lever, in the present instance, to the left across the detent than to the right from the respective outer limits of movement of the lever end. 45 In other words the lever when in the position shown in Figs. 2 and 7 relative to the detent 58 is in neutral position and when spaced to the right from the detent point the clutch member 47 is in engagement with the left hand gear 43, and when the pointed end of the lever is disposed at the left side of the detent point and in a position corresponding to the position shown in Figs. 2 and 7 the clutch member 48 will be in engagement with the right hand gear 43.

In order to cause an automatic reversing of the direction of movement of the head 13 when it has traveled a predetermined distance around the table part 3, and also to 60 effect an automatic stopping of the move-

ments thereof when it has returned to its initial starting position, the inner end of the head is provided, in the present instance, at opposite sides of its axis with dogs 59 and 59^a, one for contact with one side and the other for contact with the other side of a finger 60, which fixedly projects from the axially shiftable shaft 54 at predetermined points in the forward and backward revolute movements of the head 13. For instance, when the head 13 has completed its forward working stroke the dog 59 will have moved into contact with the finger 60 and effected a sufficient shifting movement of the shaft 54 to communicate a full shifting movement to the clutch member 48 to throw it from engagement with one into engagement with the other of the clutch gears 43, thus reversing the direction of movement of the head 13 and causing it to return to starting position. When the head has substantially completed its return movement the dog 59^a moves into engagement with the finger 60 and forces it a sufficient distance to place the clutch member 48 in neutral position, the detent 58 tending to prevent the shift-lever 49 from having a full reversing movement due to the coaction of the point of the detent with the longer side of the tapered or V-shaped end of the lever 49, as shown in Figs. 2 and 7. An adjustable contact-screw 61 is preferably carried by each dog 59—59^a.

The shafts 9 and 54, which are disposed in close parallel relation, carry coacting stop fingers 62 and 63, respectively, which coact to prevent a shifting of the shaft 54 to the left to effect a forward moving of the head 13 until the crank 11 has been turned to impart work-clamping movements to the clamp fingers 6 and to throw the work holding-roll 100 26 into work engaging position. Upon a movement of the shaft 9 to impart work-clamping movements to the fingers 6 the stop-finger 62 is swung from the path of movement of the finger 63 to permit a movement of the control-lever 55 and associated parts to throw the clutch-member 48 into engagement with the right hand or forward driving clutch-gear 43.

In order to prevent a shifting of the control-lever 11 and associated parts from their operative or work clamping positions, a latch-member 64, which is pivoted beneath the table 1, as at 65, projects over the inner hub end of the segmental gear 39 and has a notch 66 for engaging over a pin 67 projecting inwardly from the segmental gear 39 at one side of its axis when the lever 11, gear 39 and other parts have been turned to operative position. A finger 68, which projects from the rear side of the head 13, works under the registering beveled free end of the latch member 64 when the head completes its return stroke and effects a raising of the latch member from locking engagement with 125 130

the pin 67, thus permitting a movement of the crank 11 and associated parts to inoperative position.

The operation of my machine is as follows: A fender having been placed on the table in inverted position with the front rounded edge thereof fitting closely within the rib 4 at the outer end portion of the table part 3, which rib forms a recess which is complementary to the shape of the fender end, the operator gives the crank 11 substantially a half turn from its upright position to impart a work clamping action to the clamping-fingers 6-6, which fingers have connection with the eccentrics on the rock shaft 9. It will be understood that when the fender is placed on the table the side flanges have preferably been secured thereto so that the fingers 6-6 have their clamping action against the side bead of the fender at the inner edges of the side flanges. This is not necessary, however. The vizor strip *b* is also preferably placed in position for beading and joining its edge to the fender body, prior to placing the fender on the table. The turning down of the crank 11 to impart fender clamping movements to the fingers 6 also imparts an outward rocking movement to the finger 37 and a consequent throwing of the beading roll 14 and work holding roll 26 against the respective portions of the fender. The fender parts being in position for the rolling of the vizor bead *a* the operator moves the handle end of the clutch control lever 55 outward to move the shaft 54 to the left and to effect a shifting of the clutch member 48 into engagement with the right hand clutch gear 43. The rotation which is thus imparted to the shaft 40 and worm 41 drives the worm-wheel 42 in a direction to impart the forward stroke to the head 13 to cause the roll 14 to roll the edges of the vizor and fender body over the wire *c*. When the head 13 has reached a predetermined point in its forward stroke the dog 59 moves into engagement with the finger 60 on the shaft 54 and moves such shaft to effect a shifting of the clutch-member 48 into clutch engagement with the other clutch gear 43, thus imparting a reverse rotation to the shaft 40 and returning the head 13 to its starting position, during which return stroke the roll 14 again travels over the head *a* to effect a closer rolling or compressing of the same around the wire *c*. When the head 13 has completed its return stroke the dog 59^a will have had contact with the finger 60 and moved the shaft 54 a sufficient distance to place the clutch member 48 in neutral position, but not sufficiently to move the lower tapered end of the lever 49 to the left past the detent 58, thus stopping the operation of the beader until the operator has again moved the control lever 55 to move the

lower end of the lever 49 past the detent and throw the clutch member 48 into engagement with the right hand clutch gear 43. When the crank-arm 11 is in upright or inoperative position the finger 62 on the shaft 9 stands in the path of shifting movements of the finger 63, which is carried by the axially shiftable shaft 54 and prevents an engaging of the clutch members. The movement of the shaft 9 to operative position springs the finger 62 out of locking engagement with the finger 63. When the crank 11 has been thrown to its operative position the pin 67 on the gear 39 moves into register with the notch 66 in the catch-member 64 to permit such catch-member to drop by gravity over such pin when the head 13 has swung to move the finger 68 from supporting contact with the free end of the catch-member 64, thus effecting a locking of the crank 11 against movement from operative position until the head has again returned to its normal position when the finger 68 moves under the catch-member 64 and automatically raises it from locking engagement with the pin 67.

It is evident that I have provided a simple machine for joining vizors to fender bodies, and that the same is easily and quickly operable in a semi-automatic manner to join such parts and roll the connecting bead thereon, thus obviating the use of skilled and expensive labor, which has heretofore been necessary in work of this character.

I wish it understood that my invention is not limited to any specific construction or arrangement of the parts except in so far as such limitations are specified in the claims.

Having thus described my invention, what I claim as new, and desire to secure by Letters Patent, is,

1. In a machine of the class described, work clamping means having a rotatable control part, swingingly mounted work beading means, and mechanism having connection with and operable by movements of the control part of said clamping means to swing the beading means into and out of operative position.

2. In a machine of the class described, a work support, clamping fingers operable to clamp work to the support, work beading means, and mechanism operable to move said fingers into and out of clamping position and to simultaneously and automatically move said beading means into and out of operative position respectively.

3. In combination, a work support, clamping members movable to clamp work to the support, rotatable means for moving said fingers into and out of clamping position, work beading means, and mechanism operable by movements of said rotary means to

move the beading means into and out of operative position.

4. In combination, a work support, means operable to clamp work to said support and having a rotatable control part, a work beading mechanism having inner and outer work coacting parts mounted for jaw-like movements to place such parts into and out of operative position, and means operable to control the relative movement of said beading parts when the clamping means is operated to engage or release the work.

5. In combination, a work-supporting part, a beading mechanism mounted for orbital swinging movements relative to said part, means operable to swing such mechanism a predetermined distance in one direction and then to reverse the swinging movements thereof, and means operable to clamp work to said part and to render said first means operable.

6. In combination, a work-clamping means, a bead forming mechanism mounted for swinging movements relative to said means and having inner and outer work coacting members, means operable to impart swinging movements to said mechanism, and means for preventing an operation of said last means when the clamping means is out of work-clamping position.

7. In combination, a work support having a rounded edge portion, a member mounted for swinging movements in concentric relation to said edge portion, bead rolling means carried by said member, mechanism for imparting swinging movements to said member relative to the work supporting part, and a single means operable to clamp work to said support and to render said mechanism operable.

8. In combination, a work support, work beading means movable relative to said support for acting on work carried thereby, a single manually controlled mechanism operable to clamp work to the support and to impart predetermined movements to the beading means.

9. In combination, a work supporting part, a member mounted for swinging movements around a portion of said part, means operable to impart forward and backward swinging movements to the member relative to said part, yielding bead rolling means carried by said member, and a work holding roll movably carried by said member and movable into position relative to the member to act on the work in opposition to the bead forming means.

10. In combination, a work supporting part having a circular edge portion, a member mounted for concentric swinging movements relative to said part, means for imparting forward and reverse swinging movements to said member, a stationary gear in coaxial relation to said member, a

bead forming roll carried by said member for swinging movements therewith around the edge portion of said part, and connection between said gear and roll for imparting rotation to the roll upon a swinging movement of the member.

11. In combination, a work holding part having a curved edge portion, a member mounted for swinging movements around said edge portion, a bead forming roll carried by said member for rotary and transverse oscillatory movements, means operable to oscillate the roll to move it into and out of work feeding position, and means for rotating the roll upon a swinging movement of said member.

12. In combination, a work support having a circular edge portion, a beading roll, means carrying said roll for swinging movements around said edge portion and for rotary movements, and mechanism operable to rotate the roll upon a swinging movement of said means.

13. In combination, a work support having a circular edge portion, a member mounted for concentric swinging movements relative to said edge portion, a work shaping roll carried by said member for movements around the circular edge portion of said part, and means operable to rotate said roll in one direction when the member is swung in one direction and to reverse the rotation of the roll upon a reversal of a swinging movement of said member.

14. In combination, a work support, a work shaping roll, means carrying said roll for forward and backward swinging movements around a portion of said support, means for driving said roll and reversing its movement upon a reversal of the swinging movements of said member, and means for moving said roll into and out of operative position.

15. In combination, a swinging member, a work support mounted in concentric relation thereto, means for imparting swinging movements to said member, a work shaping part carried by said member for rotary and oscillatory movements relative thereto, means for communicating rotary movements to said part upon a swinging movement of the member, and means for oscillating said part relative to the member.

16. In combination, a swinging member, a gear concentrically carried thereby, a stationary work carrying part in concentric relation to said member, means operable in conjunction with said gear to impart predetermined forward and backward movements to said member, a gear which is stationary relative to said part, a work shaping roll carried by said member for movements around a portion of said part, and connection between said roll and stationary

gear for imparting rotary movements in first one and then the other direction to said roll when the member is swung forward and backward.

5 17. A machine of the class described having a head mounted for swinging movements, a work shaping member carried by said head for swinging movements therewith and for rotary and swinging movements relative thereto, and means for rotating said member when having revolute movements about the head axis, the direction of rotation changing with the direction of revolute movements.

10 18. A machine of the class described having a member mounted for swinging movements, a stationary gear in coaxial relation to said member, an axially yieldable work shaping roll carried by said member for swinging movements therewith, and connection between said gear and roll for imparting rotation therewith when being swung with said member.

15 19. A machine of the class described having a swinging work beading mechanism provided with an oscillatory work holding part and a bead forming part, means for moving said work holding part into operative position, and means for communicating swinging movements to said mechanism.

20 20. A machine of the class described having a swinging work beading mechanism provided with a pair of oscillatory inner 90 and outer work coacting parts, means operable to impart opposed movements in unison to said parts to move them into and out of work coacting position, and means for imparting swinging movements to said mechanism.

25 21. A machine of the class described having a movable head, an axially movable bead forming roll carried by said head, means for moving said head, and means for communicating rotation to the roll when the head is moved.

30 22. A machine of the class described having a movable head, means for moving said head; a roll carried by the head for rotary, axial and swinging movements relative thereto, means operable to swing the roll into operative position, and means for rotating the roll when the head is moved.

35 23. In a machine of the class described, a work holding part, a head movable relative thereto, a work shaping roll carried by the head for rotary, axial and transverse movements relative to the head, means operable to transversely move the roll into work 105 engaging position, means for moving the head, and means for imparting rotation to the roll when the head is moved.

40 24. In a machine of the class described, a work support, a head movable relative thereto, means operable to impart recipro-

catory movements to said head, and bead-rolling means carried by the head and operable to roll a bead upon a movement of the head, said roll having combined swinging and axial thrust contact with the work.

45 25. In a machine of the class described, a work carrying part, a head movable relative to said part, means operable to impart reciprocating movements to said head, bead-rolling means carried by the head and having an axially movable part projecting over an edge of said part, and means carried by the head and movable to coact with the work in opposition to the beading means.

50 26. In a machine of the class described, a work supporting part, a head movable relative to said part, means for moving said head, a beading member carried by the head for swinging and axial movements relative thereto, means normally maintaining said member in inoperative position, and means operable to move the member to operative position.

55 27. In a machine of the class described, a work carrying part, a head orbitally movable relative to said part, a work beading member carried by the head for movements therewith relative to said part and mounted for rotary, axial and swinging movements relative to the head, means for imparting 95 rotary movements to said member, upon a relative movement of the head and part, and means operable to move said member into operative position.

60 28. In a machine of the class described, a work carrying part, an element mounted for rotary reciprocating movements relative to said part, a work shaping member carried by said element for rotary and yielding movements in various directions relative 105 thereto, means for imparting rotary movements to the member when the element is reciprocated, and means operable to oscillate the member relative to said element to place it in work coacting position.

65 29. In a machine of the class described, a work carrying part, a head movable relative to said part, a work shaping member and a work holding member carried by said part for movements therewith and for work 110 engaging movements relative thereto, and means operable to relatively move both said members into work engaging positions.

70 30. In a machine of the class described, a work carrying part, a head movable relative to said part, outer and inner work shaping and holding members, respectively, carried by said head both for oscillatory movements relative thereto, means yieldingly retaining said members in inoperative position, and means operable to move said members in unison to operative position.

75 31. In a machine of the class described, a work carrying part, a head movable relative thereto, work shaping and holding members 115

carried by said head for movements therewith and for movements relative thereto, means operable to move said members into work coacting position and permitting the 5 work shaping member to yieldingly act on the work.

32. In a machine of the class described, a work carrying part, a head movable relative to said part, a work shaping member carried by said head for rotary and transverse movements relative thereto, a work holding member carried by the head for swinging movements relative thereto, means operable to impart rotary movements to the work 10 shaping member upon a movement of said head, and means operable to move both of said members relative to the head and into work coacting positions.

33. In a machine of the class described, a work carrying part, a work shaping mechanism movable relative to said part and having a shaping member, means for imparting movements to said mechanism and having a control part, and means operable to lock said 20 control part against movement and to move the work shaping member of said mechanism into work coacting position.

34. In a machine of the class described, a work shaping mechanism, control means for 30 said mechanism, drive means in connection with said mechanism and having a control part, control means for said part, and means for locking the control means for said part against movements when the control means 40 for said mechanism is in one position of its movement.

35. In a machine of the class described, a work shaping mechanism, means for controlling said mechanism, drive means in 40 connection with said mechanism and having a manually controlled part, and means actuated by movements of said control means and operable to lock said control part against movement when the control means 50 of said mechanism is in inoperative position and automatically operable to release said control part when said control means is moved to operative position.

36. In a machine of the class described, a work shaping mechanism having parts movable into and out of work co-acting positions, 50 manually controlled means for controlling the movements of said parts, and work clamping means having a plurality of clamping fingers automatically operable to clamp work upon a predetermined movement of said control means.

37. In a machine of the class described, a work clamping fingers, a work shaping mechanism having a pair of parts oppositely 60 movable into and out of work coacting position, and a single manually operated means operable to control the movement of said parts and clamping fingers.

65 38. In a machine of the class described, a

movable work shaping mechanism having a part movable into and out of work coacting position, means operable to control the movement of said part, and means automatically operable to lock said control means 70 upon a movement of said mechanism and to release said control means when the mechanism is moved a predetermined distance.

39. In a machine of the class described, a swinging work shaping mechanism having 75 a work shaping part, means for controlling the work engaging movements of said part, and means automatically operable to lock said control means against movement during the swinging movements of said mechanism and to release said control means when the mechanism has reached a predetermined point in its swinging movements.

40. In combination, a work support, members operable to clamp work to the support, 80 work beading mechanism mounted for reciprocating movements relative to the support and having a work beading roll, means for driving said roll and reversing its direction of rotation to correspond, and mechanism operable to impart predetermined reciprocating movements to said beading mechanism and to control the clamping action of the clamping members.

41. In a machine of the class described, a 85 mechanism mounted for revolute movements and having inner and outer work coacting parts for revolute movements therewith, means operable to relatively move both said parts into work coacting position, a 90 drive shaft, a driven shaft in connection with said mechanism, a reversible clutch connection between said drive and driven shafts, shifting means for said clutch connection, means for locking said shifting 95 means against movement, and means movable with said mechanism and co-operating with said shifting means to effect an automatic shifting of the clutch connection when said mechanism has reached a predetermined point in its movement.

42. In a machine of the class described, a work shaping roll movable into and out of work coacting position, an oscillatory work holding member movable into position 100 to coat with work in opposition to said roll, means operable to oscillate said work holding member, and means automatically operable to yieldingly move the roll into work coacting position when said member is 105 moved to work coacting position.

43. In a machine of the class described, a head, a work shaping roll carried by said head and mounted for oscillatory and yielding axial movements relative thereto, and means operable to oscillate the roll and 115 yieldingly hold it in work coacting position.

44. In a machine of the class described, a work shaping roll mounted for rotary, axial and transverse swinging movements, 120 125

- means influencing an axial movement thereof in work gripping direction, a member movable to engage work in opposition to said roll, and means operable to move said member to work engaging position and to yieldingly move the roll transversely to work engaging position.
45. In combination, a work support, a work shaping roll, means carrying said roll for reciprocatory movements relative to the work support, means for driving said roll and reversing its movement upon a reversal of the direction of movement of the roll carrying means, and means for moving said roll into and out of operative position.
46. In combination, a work support, roll carrying means mounted for relative reciprocatory movements, a beading roll carried by said means, means for imparting reciprocatory movements to the roll carrying means, and means to drive said roll in one direction or the other in accordance with the direction of relative movement of said support and roll carrying means.
47. In combination, in a machine of the class described, a work shaping roll mounted for yielding axial movements and for swinging movements, and means for imparting rotation to the roll when in any position of its movement.
48. In combination, a work support, a shaft mounted for swinging and axial movements, a roll carried by said shaft, means urging a movement of the shaft in one direction of its axial movement, and means urging the roll carrying portion of the shaft to have transverse movements toward the work support.
49. In combination, a work support, a beading roll mounted for transverse movements toward and away from said support, means acting on the roll to urge it to normally move away from the support, and means operable to yieldingly urge the roll to move toward the support.
50. In combination, a work support, a work holding roll movable into and out of work engaging position, a beading roll movable into and out of work engaging position in opposition to the holding roll, and mechanism operable to positively move the holding roll and to yieldingly move the beading roll into respective operative positions.
51. In combination, a work support, a lever member, a work coacting roll carried by said member, means manually operable to yieldingly move said member to place its roll into and out of operative position, and a beading roll for coacting with the work piece in opposed relation to said first roll.
52. In combination, work clamping fingers, work shaping means, and mechanism having a rotatable control part and operable by a single action to impart work clamping movements to said fingers and to place the shaping means in operative position.
53. In combination, work clamping fingers, work shaping means, and a control mechanism common to both said clamping fingers and shaping means.
54. In combination, work clamping fingers, work shaping means, and mechanism having a rotatable control part operable to impart predetermined movements to both said clamping fingers and shaping means.
55. In combination, work clamping fingers, work shaping means having relatively movable work coacting parts, and mechanism having a single control part operable to actuate said clamping fingers and to impart predetermined relative movements to the work coacting parts of said shaping means.
56. In combination, work shaping means having work coacting parts each mounted for movement into and out of work coacting position, and mechanism operable to positively act on one and yieldingly act on the other of said parts to move them into work coacting position.
57. In combination, a stationary work support, a shaft mounted for longitudinal and transverse reciprocatory movements relative to the support, a work beading roll carried by said shaft for movement therewith, and means operable to rotate the shaft.
58. In combination, a stationary work support, a shaft mounted for longitudinal, rocking and transverse reciprocatory movements relative to the support, a work shaping roll carried by said shaft, and means operable to impart rotation to the shaft when it is transversely moved.
59. In combination, a work support, a shaft mounted for longitudinal, rocking and transverse movements relative to the support, a work shaping roll carried by said shaft, means for rotating the shaft, and means for yieldingly controlling the swinging movements of said shaft in both directions.
60. In combination, a work support, a shaft standing on an incline relative to the top surface of the support and mounted for yielding axial movements, a beading roll carried by the shaft, and means for imparting rotation to the shaft.
61. In combination, a work support, a beading roll mounted for transverse and axial yielding movements and having its axis inclined relative to said support, and means for imparting rotation to said roll.
62. In combination, a work support and a part capable of relative reciprocatory movements, a lever pivotally carried by said part, a work coacting roll carried by said lever, a work beading roll carried by said part for movement into and out of work co-

acting position in opposition to the first roll, and means operable to move said lever to place its roll into work coacting position and to yieldingly move the beading roll into work coacting position.

63. In combination, a work holding roll and a work shaping roll mounted for opposed movements into and out of work coacting position, means urging a retraction 10 of both said rolls from work coacting position, and means operable to move said rolls into work coacting position.

64. In combination, a work support, work 15 shaping mechanism movable relative to the support, means operable to impart predetermined movements to said mechanism, control means for said last means, and work clamping means operable to lock said control means against movement when the clamping 20 means is in one position of its movement.

65. In combination, work clamping means, work shaping means, means for actuating 25 said shaping means, control means for said actuating means, and means for preventing an operation of said control means when the clamping means is in a predetermined position of its movement.

66. In combination, work clamping means having a rotatable control part, a work 30 shaping mechanism, means operable to render said mechanism active, and means for rendering said last means inoperative when the control part of the clamping means is in one position of its movement.

67. In combination, a reciprocally movable work shaping mechanism having work coacting parts movable into and out of operative position, work clamping means, and means 35 automatically operable to lock said work coacting parts in operative position when the work clamping means is in clamping posi-

tion and to unlock such parts when the shaping mechanism is at a predetermined point in its movement.

68. In combination, a movable work shaping mechanism having a part movable into and out of work coacting position, means operable to control the movement of said part, and means automatically operable to prevent a movement of the control means to 45 release the work coacting part from work coacting position until said mechanism has reached a predetermined point in its movement.

69. In combination, a movable work shaping mechanism having a part movable into and out of work coacting position, means operable to control the movement of said part, and means automatically operable to lock said control means in one position and 50 to release the control means when said mechanism has been moved a predetermined extent.

70. In combination, a movable work shaping mechanism having a part movable into and out of work coacting position, means operable to control the movement of said part, and a latch member automatically operable to lock said control means in position 55 to retain said part in work coacting position when the mechanism has been moved from its initial starting position and to release said control means when the mechanism has returned to its starting position.

In testimony whereof, I have hereunto 70 signed my name to this specification in the presence of two subscribing witnesses.

FRITZ RUNDQUIST.
